John Goulding, of Boston. Ms.:
Letters Patent

The Schedule referred to in these Letters Patent, and making part of the same, containing a description in the words of the said John Goulding himself, of his improvement, in the mode of preparing Hatchelling hemp, flax, tow or manilla grass & producing thereby a continuous strain or sliver -

To all persons to whom these presents shall come: I John Goulding of Boston, in the County of Suffolk & Commonwealth of Massachusetts, machinist, sends greeting. Be it known that I the said John Goulding have invented, constructed made and applied to use a new useful improvement in the mode of preparing & hatching hemp, flax tow or manilla grass. Producing thereby a continuous train or fiber. Specified & described in the words, figures & plates following whereof annexed. Fig. 1st represents a breaker used to break, prepare and hatchell the hemp, (flax or tow or grass) from which yarn is to be spun.

T is the trough into which the hemp is laid X is the roller under which the hemp passes from T.B.B are rollers between which the hemp passes to be received by the first or receiving cylinder A. this cylinder has iron or steel teeth or pins &c. projecting about two inches from its outer surface which may be put through wood or set in iron or other metal, these pins are set in rows nearly across & all around the cylinder the pins equidistant & in quincunx order so that the pins in each row shall be neither exactly behind the pins in the preceding row nor exactly before the pins in the succeeding row. F.F.F.

are wires with wires or rods running from head to head & fixed therein -
I. Q. are wires hung or fastened to the edges or rim of cylinder & by staples (as
in fig. 2 II. or by a joint & screw these wires go across and upon the outer sur-
face of the cylinder & between the rows of teeth or pins L. L. It is a piece of iron
or metal fixed upon the frame over which the wires pass as the cylinder
rotates. M. M. are springs fastened upon the inside of said cylinder and attached
through the surface of the cylinder by a stirrup to the wires Q. Q. so as to bring
them back to their places on the outer surface of the cylinder after they have
been passed by passing over the piece of metal L. C is the second cylinder

which has teeth of iron or steel projecting from its surface about one half of an inch & set as described in cylinder A, but inclined slightly forward. C has pins, corresponding to G.G. & springs corresponding to M.M. & a piece of iron or metal, K, corresponding to K. on cylinder A. O (on cylinder C) is a reel corresponding to but smaller than F on cylinder A. D.D are rollers which convey the hump 3. from cylinder C. g is a tunnel through which the hump passes. E is a can to receive the hump from D.D. R is a band that goes round the pulley on shaft 5 & carries cylinders A & C. S is a shaft that has a gear on the other end that gears into cylinder C. When the breaker is in operation the revolving motion of cylinder C is greater than that of A & in a degree proportioned to the requirement of the article to be manufactured & the two cylinders A & C. may be geared together so as to give them the relative motion required. The plates annexed hereto above referred to represent one of my breakers adapted & applied to the preparing yarn from common Russia hemp or flax or tow or grass. The cylinders A & C (fig 11) are about three feet in diameter & fourteen inches in width, the teeth or pins are set in twenty two rows each row contains ten teeth or pins, and occupies about eight inches of the middle of the width of the cylinder so as to leave a vacant space of about three inches on each side or edge of the surface of the cylinder, cylinder C has one hundred & forty eight rows of teeth, and twenty teeth in a row, the rows set as in cylinder A. Cylinder C revolves about sixteen times to each revolution of cylinder A. The other parts of the machine have the relative proportion exhibited on the plates. The process is as follows: the hump 3. is weighed out in handfuls or parcels of about six oz. each - each parcel is denoted by hand & laid in trough T on a revolving upon in layers, so that the end of each layer towards the breaker shall be about eighteen inches from that of the parcel or layer preceding it, the hump is then passed from the trough T under the roller X & between the rollers BB and is received by spades under cylinder A where it is crowded & pressed in among the teeth & folded down upon the wires G.G. by the rods or wires on the reels F.F.F. which turn in between the rows of teeth for that purpose, as the wires G.G. reach the piece of metal K, they are raised by the spades & successively other dividers & thrown out the hump from the teeth of the cylinder A so that it may be received by cylinder C & the wire G.G. which it now holds the rods & spades the hump among the

9023 X

still up and on to the wires 46, as on cylinder A, as the wires reach the piece of metal A they are raised by flaps over it & disengage the silver or silvering so that it may be more easily drawn through the tunnel q by the cylinder rollers E, D, which deliver it into can E, on both cylinders as the wires 46 pass over H & A, they are drawn back to their places by the springs H, M, on the inside of the cylinder. Ten or more of the cans E filled with the silver or silvering A may be placed at the feeders B, B & the described process of hatching may be repeated as often as may be necessary. The diameter of the cylinders must be varied according to the length of the staple of the article to be manufactured - a short staple requiring a cylinder of a smaller diameter.

What I claim as my invention is the above described mode of preparing and hatching hemp, flax, tow or manilla grass, & producing thereby a continuous train or sliver. In testimony that the above is a true specification of my said improvement I have hereunto set my hand the twenty-fifth day of April.

In the year of our Lord eighteen hundred & thirty-five -
